UNITED STATES PATENT OFFICE

CHARLES P. KUEHNER, OF NORTH PROVIDENCE, RHODE ISLAND

LINKING MACHINE

Application filed April 17, 1930. Serial No. 445,007.

This invention relates to a chain machine for connecting elements together by a link or the like; and has for its object to provide automatic mechanical mechanism for permanently linking elements which have been temporarily connected together.

A further object of the invention is to provide a machine which will receive work in sheet metal form in which the elements are definitely positioned one relative to the other and operate upon the same by inserting and closing a wire link through adjacent elements to flexibly connect them together.

A still further object of this invention is to provide a machine for forming and passing links through definitely positioned elements by rectilinear movements and avoiding the twisting or rotary action of any of the forming mechanism.

A further object of this invention is to cause the operation of the parts to act in such directions and in such sequence that the wire link is prevented from adhering to the forming tool upon its being withdrawn from its shaping carriage.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a top plan view of the machine; Fig. 2 is a perspective view of the feeding mechanism and carriage mechanism of the machine;

Fig. 3 is a sectional view through the wire feeding mechanism of the machine.

Fig. 4 is a top plan view of a portion of the work which is fed into the machine;

Fig. 5 is a top plan view of the work after its elements have been linked together;

Fig. 6 is a fragmental detail showing the position of the wire link before being severed;

Fig. 7 is a similar view showing a different operating position of the parts;

Fig. 8 is a similar view showing a more advanced position of the parts;

Fig. 9 is a fragmental top plan view of the feeding mechanism and carriage with the top levers and other parts removed;

Fig. 10 is a top plan detail view of the carriage;

Fig. 11 is a fragmental section thereof;

Fig. 12 is a fragmental section on line 12-12 of Figure 10;

Fig. 13 is a sectional view through the operating plunger of the carriage and its operating pin mechanism;

Fig. 14 is a section through the mounting of the work feed mechanism on the bed plate;

Fig. 15 is a section through the work feed mechanism at right angles to that shown in Figure 14;

Fig. 16 is a sectional view through different parts of the work feeding mechanism;

Fig. 17 is a perspective view of the pawl and reciprocating carriage on which it is mounted for feeding the work into operating position.

This invention is related to my co-pending application Serial No. 380,365, filed July 23, 1929, and alludes to the placing of the links into the elements of the blank before the temporary connections between the gem setting elements are severed; and the following is a detailed description of the present embodiment of a machine for accomplishing this advantageous result.

With reference to the drawings, 20 designates the bed plate of the machine upon which there is suitably mounted a drive shaft 21 operated by a hand wheel 24, or a belt, not shown, engaging tight or loose pulleys 22, 23, and upon this shaft there is mounted in spaced relation a series of suitably formed cams which operate through levers, herein-after more fully described in detail, to cause the successive sequences of operations in the machine to be automatically performed in definite timed relation.

The machine consists essentially of a feeding mechanism for the work, a feeding mechanism for the wire, and mechanism for causing the links of the wire to be partially formed and then transferred to the work and passed through the same and closed, all of

75

80

85

90

95

100

which are related in their operations, as will more fully hereinafter appear.

The feeding mechanism for the work consists of a supporting plate 25 which is mounted on the bed plate 20 by means of a single stud 26 having threaded engagement with the supporting plate as at 27, and which is clamped by means of the nut 28 in the desired fixed position to prevent rotation of the stud 26. Upon this supporting plate a body block 29 is positioned and is laterally adjustable upon the plate 25 by means of set screws 30 engaging either side to force it in one direction or the other, in which position it is firmly held by clamp screws 31 extending through suitable slots 32 in flanges on the body block and having threaded engagement with the supporting plate 25. In order to guide the body 29 in its lateral movement, a bar 33 is imbedded in the plate 25 and slides in a slot 34 in the body to act as a keyway to permit lateral movement of the body but prevent movement thereof in a direction longitudinally of the work. A slide 35 is reciprocatably mounted in a groove in the body block 29 to be moved forwardly by means of lever 36 pivoted as at 37 and operated by a cam 38, the same engaging the abutment 39 through an adjustable screw 40 which is secured in desired position in the arm 36 by means of the set nut 41, the slide 35 being returned to its starting position by means of tension spring 42 extending between the fixed hook 43 on the body and the pin 44 carried on the reciprocating slide 35.

A pawl 45 extends laterally from the slide 35 and is suitably pivotally mounted to drop by its own weight through a slot 46 into engagement with the work, which is carried through the guideway 47 to feed the same forwardly in a step-by-step movement.

The slot 46 extends but a portion of the length of the stroke of the slide 35 and upon return movement of the pawl, the same rides up over a shelf 48 which may be adjusted with a reference to the reciprocating slide to vary the length of feed desired. Upon return movement of the reciprocating slide 37, the friction block 49 which is forced against the work by means of the spring 50 prevents the work from being retracted from position. The work thus passes beneath this friction clamp at all times.

The wire 51 from which the link is formed is fed from a suitable source of supply by means of friction grip jaws 52 of a usual construction operated through lever 53 pivoted as at 54 and actuated by means of the cam 55, which jaws after release are returned by a spring 56. The cam 55 is a double acting cam to first cause the jaws to grip the wire and then advance the wire, after which they are released to be returned for an additional stroke. Before the jaws 52 are returned, a friction block 57 is forced

into contact with the wire 51 by means of the pin 58 which is actuated through adjustable stud 59 and lever 60 pivoted as at 61 by the cam 62. The block 57 is held in position by means of screw 63 and binding nut 64 which rests within a notch 65 and against shoulder 66 of the block 57 to prevent its removal therefrom. The wire 51 is fed against a stop 67 which is adjustably held in the desired position to accurately determine the length of wire to be used for the link.

The carriage which also assists in forming the link consists of dovetail block 68 slidable on the bed plate 20, between guides 69, which determine a path for the reciprocatable movement of the carriage, the same being actuated by means of cam 70 acting directly upon the carriage through friction roller 71 and held in engagement with the cam by suitable spring 72, shown in Figure 9. The carriage 68 is provided with a pair of guides 73 which are suitably held in position by means of screws 74 and side plates 75. These guides are each formed with a central groove 76 and receive between them the narrowed portion 77 of a plunger 78, which serves as a bottom former for the wire link.

An opening 79, see Figure 9, is shown in the bed plate in which there is located a pin 80 surrounded by bushing 81, both of which normally lie substantially flush with the bed plate 20. This pin is positioned directly beneath the work at the point where the wire link is positioned in the work. The pin is forced upwardly by means of lever 82, which is suitably pivoted beneath the machine and operated by a cam 83 on the drive shaft, the lever abutting against the end 84 (Figure 13) of the pin 80, which is returned to its lower position by means of a spring 85 acting between the collar 86 and the end 87 of the bushing 81.

In operation, the work 88 is advanced by its feeding mechanism above described in a path out of line with the path of the wire feed by the step-by-step operation, to a definite position. The wire 52 is fed against the stop 67, after which it is clamped by the top former 89 descending to hold the end of the wire against space guides 73 by means of the operation of the lever 90 acting through the adjustment 91 and slide 92 upon which the top former 89 is mounted. After the wire is thus bound, the severing tool 93 is operated through lever 94, adjustment 95 and slide 96 to cut an end portion 97 from the length of wire and the severing tool is returned to its raised position by means of a spring 98. The top former 89 is then pressed downwardly through lever 99, adjustment 100 and slide 92 and against return spring 101 to force the portion of the link 97 downwardly into the grooves 76 in the guide 75 into open U-shape form, as shown in Figure 7, against the bot-

tom former or upper edge of the plunger 77. After the top former 89 has completed its stroke, the carriage moves the partially formed link from the plane of the path of the travel of the wire 52 laterally of the travel of the wire, and also laterally of the travel of the work to a position beneath the work, which lateral movement occurs previous to the withdrawal of the top former from between the guides 73, thus preventing the withdrawal of the U-link from between the guides by reason of its adherence to the top former, the grooves in the guides serving to hold the U-link during this lateral movement.

When the carriage moves transversely to carry the U or partially formed U-link to the work, the plunger 78 of the carriage is positioned directly over the pin 80 and this pin 80 is then caused to rise through the action of lever 82, as described to lift the U-link upwardly and position it through openings 102 and 103 in the work 88, as shown in Figure 8, and is then held in this position by the plunger 77 and closed by bending the arms 104 of the link inwardly when engaged by the closing tool 105 which is brought into contact with the wire by lever 106 pivoted as at 107 and operated by means of cam 108 on the drive shaft, after which the plunger 78 is permitted to descend to a position flush with the surface of the bed plate 20, and the carriage returns to receive another U-link, the work and wire are fed forwardly as before, and a like cycle of operations are performed.

From the above, it will be apparent that I have provided a machine which causes round wire links to be inserted and closed through flat sheet stock elements held in definite relation to one another automatically in endless series, after which the temporary marginal strips 109 may be severed and the portions 110 used as prongs to retain a gem within the setting, all of which is accomplished without any rotary action of any of the tools to cause the work of the wire link to move about its own axis.

While I have described certain construction forms which embody the principles of my invention, it is obvious that other desired changes in arrangement may be made within the spirit and the scope of the invention as defined in the appended claims.

I claim:

1. In a linking machine, means for guiding and feeding a blank of sheet stock with spaced openings therein, means for forming a wire into U-shape, and inserting it through said openings, and means for bending the arms of the U-wire to complete the link.
2. In a linking machine, means for guiding and feeding a blank of sheet stock with spaced openings therein, means for forming a wire into U-shape at a position spaced from the path of the blank, means for transferring said U to the blank, and inserting it

through said openings, and means for bending the arms of the U wire to complete the link.

3. In a linking machine, means for guiding and feeding elements to be linked, means for guiding and feeding a wire to be associated with the elements out of line with but substantially parallel to the movement of the elements, and a carriage for transferring a portion of said wire beneath the said elements. 70

4. In a linking machine, means for guiding and feeding elements to be linked in one direction, means for guiding and feeding a wire to be associated with the elements in the opposite direction out of line with but substantially parallel to the movement of the elements, and a carriage for transferring a portion of said wire laterally to a position beneath said elements. 80

5. In a linking machine, means for guiding and feeding elements to be linked in one direction, means for guiding and feeding a wire to be associated with the elements in the opposite direction, means for severing a portion from the wire, and a carriage for assisting in forming and transferring the severed portion of the wire to a position beneath the elements. 90

6. In a linking machine, means for guiding and feeding elements having spaced openings, means for guiding and feeding a wire to be associated with the elements, means for severing a portion of the wire, a carriage, a former cooperating with said carriage to form said severed portion into an open U-shape link, means for transferring said carriage to position said U-link in said spaced openings, and means for closing the arms of the U-link into completed form. 100

7. In a linking machine, means for guiding and feeding elements having spaced openings, means for guiding and feeding a wire to be associated with the elements, means for severing a portion of the wire, a carriage having a plunger therein, a former cooperating with said carriage to form said severed portion into an open U-shape link, means for operating said plunger to pass the arms of the U-link through the spaced openings, and means for closing the arms of the U-link into completed form. 110

8. In a linking machine, a bed plate, means for feeding elements having spaced openings, means for feeding linking wire, a severing tool, means for holding said wire during the operating of said severing tool comprising a former for engaging the upper side of said wire and a carriage slidable on said bed plate and provided with spaced grooved guides to engage the under side of said wire, means to operate said former subsequent to the severing of said wire to force the same downwardly between said guides and cause the wire to become U-shape 120

125

130

and positioned in said groove, means for moving said carriage and the U-link formed therein to a position beneath said elements, and over a pin reciprocatably mounted in the bed plate, a plunger slidably mounted in said carriage and serving as a bottom shaper for the U-link, said plunger being located over said pin when the carriage is beneath the work, means for causing the pin to force the plunger upwardly to position the link in the spaced openings, a closing tool positioned above the elements, and means for operating the closing tool subsequent to the positioning of the link in the spaced openings to close the same with its ends in abutting relation.

9. In a linking machine, a bed plate, means for feeding elements to be linked comprising a base plate, a stud for clamping said base plate in adjusted position thereon, a body portion having a groove forming a slideway to guide the work therein, a reciprocating feed bar, a pawl mounted thereon for engagement with the elements to advance the same, and a friction clamp to hold the elements during the return of the pawl for an additional gripping bite, means for feeding the linking wire comprising a friction jaw for gripping and advancing the same, a stop to limit the advance movement, and a friction jaw to hold the wire during the return of the gripping jaws for again advancing the wire, a severing tool, means for holding said wire during the operating of said severing tool comprising a former for engaging the upper side of said wire and a carriage slideable on said bed plate and provided with spaced grooved guides to engage the under side of said wire, means to operate said former subsequent to the severing of said wire to force the same downwardly between said guide and cause the wire to become U-shape and positioned in said groove, means for moving said carriage and the U-link formed therein to a position beneath said elements, and over a pin reciprocatably mounted in the bed plate, a plunger slidably mounted in said carriage and serving as a bottom shaper for the U-link, said plunger being located over said pin when the carriage is beneath the elements, means for causing the pin to force the plunger upwardly to position the link in the spaced openings, a closing tool positioned above the elements, and means for operating the closing tool subsequent to the positioning of the link in the spaced openings to close the same with its ends in abutting relation.

10. In a linking machine, means for guiding and feeding a blank of sheet stock with spaced openings therein, means for forming a wire into U-shape at a position spaced from the path of the blank, means for transferring said U wire to a position beneath the blank stock and inserting it through said openings and means for bending the arms of the U wire to complete the link.

11. In a linking machine, means for guiding and feeding a blank of sheet stock with spaced openings therein, means for forming a wire into U shape at a position spaced from the path of the blank stock, means including a carriage for transferring said U wire to the blank stock and inserting it through said openings and means for bending the arms of the U wire to complete the link.

12. In a linking machine, means for guiding and feeding a blank of sheet stock with spaced openings therein, means for forming a wire into U shape at a position spaced from the path of the blank, means including a carriage for transferring said U wire to a position beneath the blank stock and inserting it through said openings and means for bending the arms of the U wire to complete the link.

13. In a linking machine means for feeding elements having spaced openings therein, a carriage provided with forming tool members, means for feeding a wire adjacent said forming members, means cooperating with said forming tool members to shape said wire into a partially formed link, means for moving said carriage and partially formed link therein adjacent said elements, means for inserting a portion of said partially formed link through said spaced openings and means for closing said partially formed link into completed form.

14. In a linking machine, means for guiding and feeding a blank of sheet stock with spaced openings therein, a carriage provided with forming tool elements, means for feeding a wire adjacent said forming elements, means cooperating with said forming tool elements to shape said wire into U shape, means for moving said carriage and U shaped wire therein adjacent said elements to be linked, means for inserting a portion of said U shaped wire through said spaced openings and means for acting on the U shaped wire to secure it in place.

15. In a linking machine, a carriage provided with forming tool elements, means for feeding a wire adjacent said forming elements, means cooperating with said forming tool elements to shape said wire into a partially formed link, means for feeding a blank having spaced openings therein at a position spaced from the path of the wire, means for moving said carriage and partially formed link therein adjacent said blank having spaced openings therein, means for inserting a portion of said partially formed link through said spaced openings and means for closing said partially formed link into completed form.

16. In a linking machine, means for feeding a blank having spaced openings therein to be linked, a slidably mounted carriage provided with forming tool elements, means for feeding a wire adjacent said forming tool ele-

- ments, means cooperating with said forming tool elements to shape said wire into a partially formed link, means for moving said carriage and partially formed links therein to a position adjacent said blank to be linked, means for inserting said partially formed link through said spaced openings, and means for closing said partially formed link into completed form.
- 10 17. In a linking machine, means for feeding a blank having spaced openings therein to be linked, a slidably mounted carriage provided with forming tool elements, and a plunger therein, means for feeding a wire adjacent said forming tool elements, means cooperating with said forming tool elements to shape said wire into a partially formed link, means for moving said carriage and partially formed link therein to a position adjacent said blank to be linked, means cooperating with said plunger for inserting said partially formed link through said spaced openings, and means for closing said partially formed link into completed form.
- 15 18. In a linking machine, means for feeding a blank having spaced openings therein, a carriage provided with forming tool elements, means for feeding a wire adjacent said forming elements, means cooperating with said forming tool elements to shape said wire into a partially formed link, means for moving said carriage and partially formed link therein to a position adjacent said blank having spaced openings therein, means including the forming elements to retain said partially formed link in proper position in said carriage during the moving thereof, means for inserting a portion of said partially formed link through said spaced openings and means for closing said partially formed link into completed form.
- 20 19. A machine comprising a movable carriage provided with forming tool elements, means for feeding blank stock adjacent said forming tool elements, means cooperating with said forming tool elements to form said blank stock into a partially formed unit, means for feeding a blank having spaced openings therein to a position spaced from the path of movement of the blank stock, means for moving said carriage and partially formed unit therein to a position adjacent said blank having spaced openings, means for inserting a portion of said unit through said spaced openings and means acting on said unit to secure it in place.
